CLAIM

The ornamental design for an electronic key locator set, as shown and described.

DESCRIPTION

FIG. 1 is a front perspective view of an electronic key ring locator set embodying my new design, showing a control unit and two key ring fobs.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof; and,

FIG. 7 is a bottom plan view thereof.

The broken lines shown on the drawings are for illustrative purposes only and form no part of the claimed design.
